UNITED STATES PATENT OFFICE.

JACOB A. HYLE, OF ATLANTIC CITY, NEW JERSEY, AND CLARENCE R. KEATLEY, OF LOS ANGELES, CALIFORNIA, ASSIGNEES TO CONTINENTAL RAILWAY SUPPLY CORPORATION, A CORPORATION OF DELAWARE.

RAILWAY-RAIL ANCHOR.

Application filed January 7, 1928. Serial No. 245,166.

This invention relates to new and novel improvements in one-piece rail anchors or anti-creepers especially designed to be secured to the base portion of railway track rails and in engagement with stationary parts of the railway road bed for the purpose of preventing longitudinal displacement of the rails during the travel of the rolling stock thereover.

10 The main object of the invention is to provide a simple, novel, strong, durable, economical and thoroughly efficient anchor from a single piece of high grade spring steel of suitable dimensions and possessing maximum 15 strength, which may be easily and readily applied to the base of a track rail and fixedly maintained in the proper operative position thereon, and which will always effectively grip and clamp the track rail and cooperate 20 with a stationary part of the railway road bed to prevent the track rail from creeping.

Another object of the invention is to so construct our improved device that it will always maintain an extremely tight grip and 25 effective frictional engagement with the track rail under any and all conditions of service.

Further objects of the invention are to so 30 construct the novel rail anchoring device that it will successfully resist creeping of the track rail; that it may be easily removed and reapplied any number of times, and at the same time retain its effective tension and gripping power; that it provides the desired 35 bearing surface in contact with the railway tie, and extends downwardly to the middle portion of the tie into the road ballast, and is so shaped at its lowermost portion where it enters the road ballast that the vibration 40 and wave motion of the track rail will push or force the ballast apart, so that it will not be in constant contact with the said ballast thereby avoiding interference with the railway electric signaling system now employed; 45 that it possesses the necessary resiliency in securing it to the track rail; that it is thickened at the points where the greatest strength is required.

The foregoing and such other objects as 50 may appear from the ensuing description are accomplished by the construction, location, arrangement and combination of the parts hereinafter more fully described, illustrated by the accompanying drawings, and particu-

larly pointed out in the claims appended 55 hereto, it being understood that slight changes in the precise form, proportions, and minor details of the construction may be resorted to without departing from the spirit or sacrificing any of the advantages of the 60 invention.

In the accompanying drawings forming a part of this specification it will be seen that:

Figure 1 is a perspective view of the improved device embodying our invention applied to one edge of the track rail in the position it assumes before being secured to the opposite edge of the rail, and showing the track rail in cross section and a portion 70 of a railway tie broken away.

Figure 2 is a similar perspective of the novel device showing it applied to the track rail in its operative position.

Figure 3 is a side elevation showing the 75 anchoring device removed from the track rail.

Figure 4 is a plan view of the same, and Figure 5 is an end view thereof.

In the embodiment of our invention as illustrated, it will be seen that the numeral 1 designates a railway track rail and 2 an underlying cross-tie forming a stationary part of the rail bed and supporting the rail 1, the said rail having a tendency to creep, 85 when subjected to the heavy and intense strain caused by the passage or travel of the rolling stock thereon.

Our improved and novel rail anchor is 90 formed from any suitable or desirable metal, but is preferably made from a single piece or flat bar of high carbon spring steel of the desired or required dimensions, and may be of any desired thickness or width, said anchor being provided with a jaw member 3, 95 which is adapted to overlap and clamp the inclined upper surface of the track rail base, the said jaw member being formed or bent comparatively close to the body portion at the point 4, so that when it is forced on the 100 rail the upper portion of the jaw will spring upwardly and at the same time always maintain an entirely tight grip on the inclined surface of the rail base.

It will be perceived that the sinuous or 105 substantially S-shaped body portion 5 extends downwardly to about the middle portion of the cross-tie 2, and the said down-

wardly extended portion is made thinner and weaker from the point 6 to the point 7, to furnish the desired resiliency or spring action when being applied to the rail and to insure a strong and firm gripping effect onto the rail, while the jaw member, and the other portion of the body are thickened to furnish the desired strength. Between the body portion 5 of the anchor, and its outer upright end portion 8, it is provided with a series of recesses or depressions 9 to furnish additional resiliency and spring action, and also to permit the arm portion 10 of the anchor to spring upwardly when being forced onto the track rail.

The lowermost portion of the anchor is so shaped where it projects into the track ballast that the vibration and wave motion of the rail during the travel of the rolling stock over the rail will cause said lowermost portion to push the ballast apart, thus preventing constant contact of the anchor with the ballast and thereby avoiding interference with the usual railway electric signaling systems now employed.

In applying our improved anchor to the track rail it is placed on the rail by the hand of the trackman or employee in the position substantially as shown in Fig. 1 of the drawings; it is then given as many blows as is necessary at the jaw portion 11 by a suitable spike maul or hammer until the jaw portion is opened and forced upwardly until it is caused to assume the position substantially as shown in Fig. 2 of the drawings, with an intense grip on the upper inclined surface, as well as the lower face of the rail, then striking it a blow at the point 12 will cause the free end portion 8 to move outwardly and to tightly snap over and grip the other edge of the rail base into its operative position, as clearly shown in Fig. 2 of the drawings.

The outer free end of the anchor normally extends in a horizontal plane above the lower level of the base portion of the jaw member, so that when the anchor is adjusted to the track rail there will be continuous pressure upwardly by the said end against the lower face of the rail, hence when a blow is struck against the anchor at the point 12, the outer end portion will be caused to immediately snap upwardly and tightly grip and clamp the edge of the rail base, and is always maintained in such position due to the high spring tension exerted by the sinuous body portion and the particular construction of the anchor, and owing to the continuous upward pressure of its outer end there is no possibility of the anchor loosening or dropping off from any cause whatsoever.

It will be observed that there is a space 13 formed between the body portion of the anchor and the arm portion 10 so that the

said arm can spring either way, that is upwardly or downwardly when applying the anchor to the rail in the manner hereinbefore described.

The anchor can be readily removed by 70 striking the outer end portion at 14 a downward blow, which will cause said end portion to spring forwardly and assume the position substantially as shown in Fig. 1, when by striking the jaw member on each 75 side a few times the anchor may be readily slipped off the rail, or a special tool may be employed in removing the anchor from the track rail.

The body portion of the anchor extends 80 downwardly to a point terminating about midway of the height of the cross-tie with which it contacts thereby preventing any tendency of the tie to rock sidewise when 85 intense strain is imparted thereto, thus insuring greater stability and unity of parts.

It will be understood that our improved anchor may be formed in any suitable or desirable manner, but is preferably made from one piece of steel of the same size 90 throughout its length and is forged or pressed into the desired or required shape, such as shown in the drawings.

Having thus described our invention, what we claim and desire to secure by Letters Patent is:—

1. A single piece rail anchor comprising a metallic bar formed with a jaw member, and downwardly extended body portion having a thinner portion formed between its upper and lower points, and an outwardly extended arm portion terminating with an upright outer end, said arm portion being provided with a plurality of depressions intermediate its length.

2. A single piece rail anchor comprising a metallic bar formed with a jaw member at one end, a downwardly extended sinuous body portion having a thinner portion between its upper and lower points, and an outwardly extended arm terminating with an upright clamping portion at its other end, said arm portion being provided with a series of recesses intermediate its length.

3. A single piece rail anchor comprising a metallic bar made of high grade steel formed with a jaw member at one end, a downwardly projected sinuous body portion formed with a thinned portion between its upper and lower points, and an outwardly extended arm terminating with an upright clamping portion at its other end, said arm portion having a plurality of depressions formed therein intermediate its length.

4. A single piece rail anchor comprising a 125 metallic bar made of high grade carbon steel formed with a jaw member at one end thereof, a depending sinuous body portion in contact with a cross-tie and terminating about the central portion of said tie, said 130

body portion having a thinner portion formed intermediate its height, an outwardly extended arm terminating with an upright clamping portion at the other end of the anchor, said arm portion having a plurality of depressions formed in its lower face intermediate its length.

5. A single piece rail anchor comprising a bar made of high grade steel having a jaw member formed at one end, a sinuous down-

wardly extended body portion having a thinned portion intermediate its height, and an outwardly extended arm portion with an upright clamping portion at the other end of the anchor, said arm having a plurality of depressions formed therein intermediate its length. ¹⁵
